THE NORRIS PETERS CO., PHOTO-LITHO., WASHINGTON, D. C.

UNITED STATES PATENT OFFICE.

EUGENE H. ALLMAN, OF MOBILE, ALABAMA.

ATTACHMENT FOR PLOWS.

SPECIFICATION forming part of Letters Patent No. 748,682, dated January 5, 1904.

Application filed February 25, 1903. Serial No. 145,064. (No model.)

To all whom it may concern:

Be it known that I, EUGENE H. ALLMAN, a citizen of the United States, residing at Mobile, in the county of Mobile and State of Alabama, have invented a new and useful Attachment for Plows, of which the following is a specification.

My device is an attachment for plows, and is in the nature of a subsoil-plow; and the object is to construct a plow adapted to press the earth to one side and loosen it up, but not to throw the subsoil to the top, where it would dry out and become "baked."

In the accompanying drawings, Figure 1 is a perspective view of my improvement, showing it attached to a plow. Fig. 2 is a perspective view of the bracket detached. Fig. 3 is a detail view of the connecting-bar. Figs. 4, 5, and 6 are detail views of the shoe detached.

In carrying out my invention I construct a bracket A, adapted to be secured to one side of a plow-beam. This bracket comprises a forwardly-extending horizontal member A' and a forwardly and downwardly inclined member A², the two members being connected at the rear by the curved portion of the bracket and also by the integral oblique strengthening member A³. The forward end of the member A' is enlarged, and this enlarged portion is vertically slotted at A⁴, while toward the rear the member A' is longitudinally slotted at A⁵. The member A² has a plurality of perforations A⁶.

The connecting-bar C is a flat straight piece of metal having a plurality of perforations C' in its upper portion adapted to aline with the perforations A⁶. The bar also has a perforation C² adjacent its lower end.

The point B of the subsoiler is substantially diamond-shaped, bent in the center, the ends being sharpened and extending forward of the central portion. On the rear side are centrally formed a pair of perforated lugs B'.

Bolts are passed through the plow-beam adapted to aline with slots A⁴ and A⁵, and in

assembling the parts of my attachment the bracket A is secured to the sides of the plow-beam, the length of the slot A⁵ allowing for variations in the positions of the bolt-holes 50 in the plow-beam. The bar C is secured, by means of suitable bolts, to the perforated member of the bracket, and the lower end of the bar fits between the lugs B', and by means of bolts and nuts of the common type 55 the point can be secured to the bar at the desired angle. The plurality of perforations in the member A² and bar C permits the depth at which the point will work to be varied, and the vertical slot A⁴ permits adjustment of the bracket, whereby the angle of the point can be adjusted so that it will always be in alinement with the plow with which it is used. The point is sharpened at each end, and when one end becomes worn 65 the point can be reversed. In practice I prefer to have the bolt which connects the beam to the handle pass also through the slot A⁵.

Having thus fully described my invention, 70 what I claim as new, and desire to secure by Letters Patent, is—

The combination with a plow-beam, of a bracket having a horizontal, forwardly-extending portion, said portion having an enlargement at its forward end, said enlargement being vertically slotted, and having a longitudinal, horizontal slot adjacent the rear end of the horizontal portion, a perforated, rear, downwardly and forwardly inclined portion, a central, curved, connecting portion, a straight, flat bar having a plurality of perforations formed adjacent its upper end and adapted to be adjustably secured to the perforated downwardly-extending portion of the bracket, and a plow-point adapted to be pivotally connected to the lower end of the straight bar. 75 80 85

EUGENE H. ALLMAN.
